UNITED STATES PATENT OFFICE.

CHARLES H. GREENWOOD, OF LA SALLE, NEW YORK, ASSIGNOR TO THE CARBORUNDUM COMPANY, OF NIAGARA FALLS, NEW YORK, A CORPORATION OF PENNSYLVANIA.

DRIER.

Application filed November 9, 1925. Serial No. 67,758.

This invention relates to driers and especially driers of the rotary type, and relates more particularly to means for effectively heating the drier.

According to the present invention it is proposed to provide means by which oil may be used as a fuel for heating the shell of a drier without burning the drier or producing hot spots or without undesirable effects.

It is well understood by those skilled in the art that the burning of oil requires a temperature in the combustion chamber of approximately 1,600° F. This is far too hot for the ordinary type of drier. If, therefore, oil is to be used as a fuel it is necessary that it be burned efficiently.

By means of the present invention it is possible to burn the oil under more efficient conditions and yet prevent burning of the shell of the drier.

The invention may be readily understood by reference to the accompanying drawings which illustrate more or less diagrammatically one embodiment of the invention, but it will be understood that I do not confine myself to the particular construction therein disclosed as various changes and modifications are contemplated within the scope and spirit of my invention.

In the drawing:

Figure 1 represents a longitudinal vertical section through a drier heated in accordance with my invention; and

Figure 2 represents a vertical transverse section in the plane of line II—II of Figure 1.

Referring more particularly to the drawing, 5 designates a chamber or housing for the drying shell 6 which is preferably of the rotary type. At one end of the shell 6, which is of the usual construction, is a supply hopper 7 through which a material to be dried may be introduced into the shell and at the opposite end of the shell is a discharge hopper 8. Supported on a suitable foundation 9 within the chamber 5 and below the shell 6 is a suitable combustion chamber 10 having an oil burner 11 at one end thereof.

The combustion chamber 10 is of a refractory nature having walls of high thermal conductivity. It is preferred that this chamber be made of silicon carbide, this

substance being highly refractory and yet being a good conductor of heat. The end 12 of the chamber opposite the burner 11 is open.

In the operation of the drier the oil is combusted within the chamber 10 at a high temperature. The walls of the chamber being a good conductor of heat radiate a considerable amount of heat of combustion directly to the shell 6 of the drier. The hot gasses of combustion emerge from the open end 12 of the combustion chamber 10 and circulate through the housing 5. At the upper part of one end of the housing there is a conduit 13 through which gases may be led from the chamber 5 into the discharge end of the shell 6. At the opposite end of the shell 6 is a pipe 14 through which gases may be withdrawn from the interior of the shell, and a fan 15 may, if desired, be employed to insure of the proper circulation of gases. The hot gases circulating about the chamber 5 flow through the passage 13 where they contact directly with the material in the shell to be dried. In this manner the material to be dried is heated by direct radiation from the combustion chamber 10, then heated by the circulation of gases outside of the shell and further heated and dried by the passage of the hot gases through the shell. By reason of the fact that the oil is initially burned within the refractory combustion chamber 10 the high temperature flame does not impinge directly against the walls of the shell to burn or otherwise destroy them. At the same time, heat is effectively radiated so that the heat is used efficiently. By the time that the gases of combustion emerge from the open end of the chamber 10 they have cooled sufficiently that their circulation directly about the shell is not injurious. After they have passed through the conduit 13 they are sufficiently cool so that they can be safely passed through the shell without danger of injury to the material to be dried or without injury to the shell itself.

I claim:

1. The combination with a drier of means for heating the drier by radiation including a radiating combustion chamber having a fuel burner, a circulating chamber about the drier through which hot gases from the radiating combustion chamber may flow, and a

conduit leading from the circulating chamber into the drier and means for withdrawing gases from the drier.

2. The combination with a drier and a chamber within which the drier is mounted, of a silicon carbide combustion chamber within the heating chamber and below the drier.

3. The combination with a drier and a heating chamber within which the drier is mounted, of a silicon carbide combustion chamber within the heating chamber and below the drier, said combustion chamber having a fuel burner at one end thereof and having its other end opening into the heating chamber.

4. The combination with a drier and a heating chamber within which the drier is mounted, of a silicon carbide combustion chamber within the heating chamber and below the drier, said combustion chamber having a fuel burner at one end thereof and having its other end opening into the heating chamber, and means for conducting gases from the heating chamber into the drier.

5. The combination with a cylindrical rotary drier and a heating chamber within which the drier is mounted, of a silicon carbide combustion chamber within the heating chamber and extending longitudinally under the drier, said combustion chamber having a fuel burner at one end thereof and having its other end opening into the heating chamber.

35 6. The combination with a horizontally arranged cylindrical rotary drier and a heating chamber within which the drier is

mounted, on an oil burner below the drier, a silicon carbide heating chamber extending forwardly under the drier from the fuel burner, said combustion chamber opening into the heating chamber, and a conduit leading from the heating chamber into one end of the shell of the drier.

7. The combination with a horizontally arranged cylindrical rotary drier and a heating chamber within which the drier is mounted, of an oil burner below the drier, a silicon carbide heating chamber extending forwardly under the drier from the fuel burner, said combustion chamber opening into the heating chamber, a conduit leading from the heating chamber into one end of the shell of the drier, and means connected with the other end of the shell of the drier for drawing gases through the shell.

8. The combination with a drier and an enclosing structure therefor of a combustion chamber within the enclosing structure and below the drier which is highly refractory and which is a good conductor of heat, and a fuel burner at one end of said combustion chamber.

9. The combination with a rotary drier and an enclosing structure therefor, of a silicon carbide combustion chamber in the enclosing structure under the drier having a fluid fuel burner at one end thereof and having its other end opening into the enclosing structure.

In testimony whereof I have hereunto set my hand.

CHARLES H. GREENWOOD.
